UNITED STATES PATENT OFFICE.

JOHN WILLIAM DIXON, OF CARLISLE, OHIO.

WINDOW-WASHER.

SPECIFICATION forming part of Letters Patent No. 448,758, dated March 24, 1891.

Application filed September 13, 1890. Serial No. 364,880. (No model.)

To all whom it may concern:

Be it known that I, JOHN WILLIAM DIXON, a citizen of the United States, residing at Carlisle, in the county of Warren and State of Ohio, have invented a new and useful Window-Washer, of which the following is a specification.

The invention relates to improvements in window-cleaners.

10 The object of the present invention is to provide a simple and inexpensive window-washer and squeegee, adapted to readily receive a sponge, cloth, or the like, and capable of enabling the rubber to be readily adjusted.

15 The invention consists in the construction and novel combination and arrangement of parts hereinafter fully described, illustrated in the accompanying drawings, and pointed out in the claim hereto appended.

20 In the drawings, Figure 1 is a perspective view of a window-cleaner embodying the invention. Fig. 2 is a longitudinal sectional view. Fig. 3 is a transverse sectional view of the window-washer. Fig. 4 is a transverse 70 sectional view of the squeegee-head.

25 Referring to the accompanying drawings, 1 designates a pole having secured to one end by means of a transverse bolt 2 a squeegee or scraper 3 and the washer 4, which are oppositely disposed on the pole, and either one can be brought into use by merely turning the pole. The window-washer 4 consists of a shank 5, cast of a single piece of metal and provided at its upper or outer end with a stationary jaw 6, and having its lower end 7 enlarged and concaved on its inner face 8, which lies adjacent to the pole and conforms to the configuration of the same, and the said lower end is provided with a perforation 9 to receive

30 the bolt 2, and has a spur or point 10, which engages the pole and prevents the window-washer turning on the bolt 2. The shank 5 is provided with longitudinal flanges 11, which extend along the edges of one of its edges and 35 form a way in which slides the stem 12 of a sliding jaw 13, which is secured to the shank by a set-screw 14, the stem 15 of which is arranged in a longitudinal slot 16 of the shank, and is adapted to move in the said slot to permit

40 the jaws 6 and 13 to clamp or release a

sponge, cloth, or the like, and the stationary jaw 6 is provided with projections 17, which prevent the displacement of a sponge or cloth.

It will be seen that the washer is capable of securely clamping a cloth, sponge, or the like, and of readily releasing the same when desired.

The squeegee or scraper 3 consists of a stem or shank 18, provided at its upper end with an integral cross-bar 19, having a flat outer 60 face 20 and a lower beveled edge 21. A sheet of rubber is secured on the upper face by a metal plate 22, and projects beyond the beveled edge, and is adapted to scrape and dry in the usual manner. The metal plate is provided with transverse slots 23, in which are arranged set-screws 24, which engage the plate and secure it at any point of adjustment, and as the rubber becomes worn it can be adjusted. The lower end 25 of the shank 18 is constructed similarly to the end 7 of the window-washer, and is provided with an opening 26 and a spur 27 to engage the pole and prevent the squeegee or scraper turning on the bolt. 70

From the foregoing it will be seen that the 75 window-scraper or squeegee and the window-washer are simple and inexpensive in construction, and by their arrangement on the pole 1 either can be readily brought into use without necessitating a change of parts. 80

What I claim is—

As a new article of manufacture, the window-cleaner, comprising the pole, the washer 4, and drier or scraper 3, diverging from the pole and having their inner ends enlarged 85 and concaved and fitting the sides of the pole and having perforations and provided with spurs engaging the pole, the outer ends of said washer and drier or scraper being provided with adjustable jaws to receive the washing 90 and drying material, and the bolt passing through the said perforations and the pole, substantially as described.

In testimony that I claim the foregoing as my own I have hereto affixed my signature in 95 presence of two witnesses.

JOHN WILLIAM DIXON.
